UNITED STATES PATENT OFFICE.

IRAD L. GARSIDE, OF PATERSON, NEW JERSEY, ASSIGNOR TO HIMSELF
AND WILLIAM BERDAN, OF SAME PLACE.

SEPARABLE BUTTON.

SPECIFICATION forming part of Letters Patent No. 240,401, dated April 19, 1881.

Application filed March 7, 1881. (No model.)

To all whom it may concern:

Be it known that I, IRAD L. GARSIDE, a citizen of the United States, residing at Paterson, in the county of Passaic, in the State of New Jersey, have invented certain new and useful Improvements relating to Separable Buttons, of which the following is a specification.

My improved button somewhat resembles that described in the patent to me dated July 27, 1880, No. 230,473, but is simpler, and on several accounts preferable. The shank is engaged by a pair of springs inclosed in the button and exerting a constant pressure toward each other. They are forced apart by the shank, which is tapered for the purpose, and when the shank is sufficiently inserted they lock under shoulders in the shank. The shank is locked directly by the springs.

When it is desired to liberate the button from the shank it is effected by a forcible turning of the button-body relatively to the shank. This, by the aid of a piece which is capable of turning partially within the button, or rather of remaining stationary with the shank when the button-body is turned, forces open the springs and induces the unlocking.

What I have termed a "pair of springs" may be made in the form of a single spring, if preferred. I will represent a modification in which that form is adopted and several changes made in other parts.

The accompanying drawings form a part of this specification.

Figures 1 to 11, inclusive, are all different views of the whole, or of parts in what I esteem the preferable construction. Fig. 1 is a side view of the button with its detachable part in place. I have added also a section of the front, which may be a polished stone, and of a rim, which binds the front tastily to what I have termed the "body" of the button proper. The parts which inclose the novelty are not in section, and are not shown in this figure. Figs.

2 to 11 represent the parts which contain the novelty. Fig. 2 is a central section with the parts locked together. Fig. 3 is a section on the line S S in Fig. 2. The relation of the parts corresponds to the view in Fig. 2. Fig. 4 is a

front view of the body with the parts locked. Fig. 5 is a view corresponding to Fig. 3, with the body of the button turned relatively to the shank sufficiently to unlock the latter. To effect this important end the body is turned about an eighth of a revolution relatively to the shank, with the effect of opening the spring sufficiently to liberate the shank. Fig. 6 is a section through the body with the mechanism removed, looking toward the back. Fig. 7 is a corresponding view, looking toward the front. Figs. 8, 9, 10, and 11 are different views of a turning piece, which is loosely fitted so as to be partially turned around in the body. Fig. 8 is an edge view. Fig. 9 is a corresponding central section. Fig. 10 is a front view, and Fig. 11 is a section on the line t t. The remaining figures represent a modification which involves some of the features of my invention, and will be described farther on.

Similar letters of reference indicate corresponding parts in all the figures where they occur.

Referring to Figs. 1 to 11, A is a front and outer rim or shell of the button. A' is a middle plate. A² is a back plate and rim, forming a junction with the middle plate, A', and constituting therewith a box, which is received within the main shell A, and secured therein by forming over the back edge of the latter, as indicated in Fig. 1.

D D are springs, one end of each of which is fixed to the back plate, A², by encircling the respective pins d. The springs are curved, as shown, and exert a considerable pressure inward by abutting against the respective pins d'. The ends D' are straight for a considerable distance, and stand in the positions shown, pressing toward the center of the button. These portions D' of the springs form the locking means which engage the shoe and shank to the button by locking under the shoulders of the shank.

B B', &c., indicate a turning piece. The turning piece lies in the center of the body, between the middle plate, A', and the back plate, A². It is reduced in diameter at each end and fits easily in corresponding holes in the plates. The hole in the back plate, A², is circular.

The hole in the middle plate, A', is mainly circular, but with a wide notch, a'. This notch receives a narrower projection, B², on the corresponding part of the turning piece. The arrangement allows the turning piece to be rotated about one-eighth of a revolution, and then forbids its turning any farther by the contact of the projection B² against one side of the notch a'.

- 10 On opposite sides of the turning piece B are deep channels b'. This form allows the straight portions D' of the springs to be received within the turning piece when the latter is in its usual position, but forces them outward when the turning piece is sufficiently turned from its normal position. The flattened portion B³ of the turning piece remaining between the cavities b has a length equal to the whole diameter of the entire turning piece B.
- 15 It performs the important function of forcing apart the spring ends when the device is turned and of receiving the force of the spring ends D' in such manner as to compel its prompt return to its original position so soon as the turning piece is removed. A rectangular mortise, b, extends longitudinally through the entire turning piece B.

G is a smooth round shoe. G' is a flat shank of a size adapted to be inserted through the 30 mortise b, and having angular shoulders G², adapted to engage with the parts D' of the springs. The shank G' is beveled at its front end or head, so that on being inserted it can easily force apart the spring ends D'. So soon 35 as the shank is forced fully home in the body of the button, or, rather, as the shank will usually be first inserted in the garment, so soon as the body is forced fully down upon the shank, the spring ends D', which have been 40 forced apart by the beveled end of the shank, snap partially together, and engage strongly under the shoulders G² and hold the body of the button firmly to the shank G' and shoe G.

When the shoe G and its attachments are 45 held stationary and the body of the button is turned relatively thereto about one-eighth of a revolution, the form of the turning piece compels the spring ends D' to move apart, so as to disengage the spring ends from under the 50 shoulders. Thus conditioned, the button may be detached; but under ordinary conditions it is held firmly.

When the button is to be applied to a garment the shank is first inserted through the 55 button-hole from the back of the garment and caused to protrude at the front. Then the body of the button is applied in such position that the front end of the shank is received in the hole b in the center of the turning piece B, 60 and the parts are pressed forcibly together. The pressure inserts the shank into the body of the button by reason that the beveled front of the shank acts wedgewise to force apart the ends D' of the springs. So soon as the 65 shank is pressed fully home the tension of the springs causes their ends D' D' to engage un-

der the shoulders G² of the head G³. The parts are now fully locked, and the button is ready to serve for an indefinite period in the usual manner.

When the parts are to be disengaged the separation can be accomplished by the partial turning of the body relatively to the shank, which will effect the disengagement by forcing the spring ends D' D' out of contact with 75 the shoulders G² of the shank G' by the cam-like action of the part B³. The proportions are such that the limit imposed on the turning motion prevents the possibility of turning so far as to hold the spring ends permanently apart. So soon as the shank is withdrawn the force of the springs promptly returns the turning piece B B', &c., to its original position, ready for re-engagement of the shank in the manner first described.

Modifications may be made in the forms and proportions of the details.

It will be understood that the ornamental front A may be varied in material, size, and pattern indefinitely.

One modification to which I attach much importance is shown in Figs. 12 to 25, inclusive. Fig. 12 is a central section. Fig. 13 is a front view of the parts shown in Fig. 12. This shows them with the shank firmly locked. 95 Fig. 14 is a corresponding view with the shank partially turned to effect its disengagement. Fig. 15 represents the same parts with the middle plate inserted. Fig. 16 is a corresponding view, showing the two parts of the button in the act of being detached by the shoe and shank having been forcibly turned relatively to each other. Fig. 17 is a front view of the back plate and rim. Fig. 18 is a cross-section thereof on the line s s. Fig. 19 is a front view of the middle plate. Fig. 20 is a section thereof on the line t t. Figs. 21 to 24, inclusive, represent the turning piece. Fig. 21 is a front view; Fig. 22, a back view; Fig. 23, a section on the line x x, and Fig. 24 a section on the line y y. Fig. 25 represents the spring detached. In these Figures 12 to 25, inclusive, a single spring serves the functions of the two springs employed in the other form. One point is held by solder E. The ends D' of the 100 springs are straight and perform in the same manner as with the two springs. The turning piece in this modification serves substantially as in the other, but is differently formed.

Parts of the invention may be used without the others. I can dispense with the projections B², and consequently dispense with the notches a' in the middle plate; but that would leave the device liable to be turned too far, and care would have to be exercised to avoid 115 leaving the button with the turning piece B B', &c., in the wrong position and with the spring ends permanently held apart.

I have termed the device a "button," and esteem that the most convenient name; but it 130 will be obvious that it can be made of small size, to serve as what are generally known as

"studs." It may be made in various sizes and materials, and serve for use or ornament, or both, in various positions.

I claim as my invention—

5 1. In a separable button, the flat head G^2 G^3 , having a beveled front and shouldered back, as shown, in combination with the flat shank G' and shoe G , turning piece B , and with a button-body having springs arranged 10 to be liberated by the turning of the parts relatively to each other as herein specified.

2. In combination with a button-body having springs, the turning piece B B' , with cams B^3 , arranged to serve relatively to the spring 15 ends D' D' , and to the shank-head G^2 G^3 and connected shoe G , as herein specified.

3. In a separable button adapted to be disconnected by the turning of one part relatively to the other, the turning piece B B' and projection B^2 , in combination with the plate A' , 20 having the notched aperture a' , arranged to serve relatively to each other, and to the shoe G , shank G' , shank-head G^2 G^3 , and locking devices D' , as herein specified.

In testimony whereof I have hereunto set 25 my hand, at New York city, this 3d day of March, 1881, in the presence of two subscribing witnesses.

I. L. GARSIDE.
